UNITED STATES PATENT OFFICE.

HENRY W. PETERS, OF BOSTON, MASSACHUSETTS.

NAME PLATE.

Application filed August 31, 1925. Serial No. 53,640.

To all whom it may concern:

Be it known that I, HENRY W. PETERS, a citizen of the United States, residing at Boston, in the county of Suffolk and State of Massachusetts, have invented a new and useful Name Plate, of which the following is a specification.

This invention relates to a name plate and the like such as used, for example, upon the radiators of automobiles. Heretofore where distinctive name plates have been used it has been found undesirable to employ enamel in the design of the name plate because, when subjected to the heat from the radiator to which the plate is attached, the enamel becomes cracked and unsightly.

It is an object of the present invention to provide a device of this character which can utilize enamel without danger of cracking, means being employed for protecting the enamel from the heat conducted through the wall of the radiator or radiating therefrom.

A further object is to provide a name plate in which the emblem or the like to be displayed thereon can be inserted readily into position and secured in place.

With the foregoing and other objects in view which will appear as the description proceeds, the invention resides in the combination and arrangement of parts and in the details of construction hereinafter described and claimed, it being understood changes in the precise embodiment of the invention herein disclosed may be made within the scope of what is claimed without departing from the spirit of the invention.

In the accompanying drawings the preferred form of the invention has been shown.

In said drawings, Figure 1 is a front elevation of a portion of a radiator having applied thereto a name plate such as constitutes the present invention.

Figure 2 is an enlarged elevation of the name plate.

Figure 3 is a section on line 3—3 Figure 2.

Referring to the figures by characters of reference 1 designates an attaching plate which can be soldered or otherwise secured to the radiator R or other supporting structure. Mounted on this attaching plate are the walls 2 of a box preferably stamped from sheet metal, one of these walls being normally extended in alinement with the front face 3 of the box. This has been indicated by

broken lines in Figure 3. The other walls, however, are soldered or otherwise fastened to the plate 1. Thus it will be seen that the structure constitutes a box into which the insert 4 can be placed. This insert can be of any suitable material. In the structure illustrated it includes a plate of metal or the like having a design cut thereinto and filled with enamel as shown at 5. Under ordinary conditions heat conducted to the box and thence to the plate 4 would crack this enamel and soon dislodge it so as to render the name plate unsightly. To eliminate this objectionable result a sheet 6 of asbestos or other material suitable for resisting the conduction of heat is placed between the attaching plate 1 and the plate 4. After these parts have been inserted into the box the bendable wall shown by broken lines in Figure 3 is bent to position against the sheet 6 and plate 4 and can be soldered or if preferred can be left so that it can be bent to open position again should it be desired to remove the contents of the box.

Obviously by providing a structure such as described the same can be applied to the radiator of an automobile and will not be affected by heat. Thus the name plate can include in its structure enamel portions and more attractive designs can be satisfactorily used than has heretofore been possible.

What is claimed is:

1. A name plate for attachment to automobile radiators and the like, including a box having an open face, a plate supported within the box including enamel, and an insulating material interposed between the plate and the back of the box.

2. A name plate for automobile radiators and the like, including an attaching plate, a box thereon having an open face, a sheet of material within the box and against the attaching plate for preventing conduction of heat from the attaching plate and a member insertable into the box and against the insulating sheet for display through the open face of the box.

3. A name plate for automobile radiators and the like including an attaching plate, a box thereon having an open face and an open side, a bendable portion adjacent the open side, a plate insertable through the open side into the box for display through the open face of the box, and a sheet of material interposed between the attaching

plate and the inserted plate for preventing conduction of heat from the attaching plate to the inserted plate.

4. A name plate for automobile radiators and the like including an attaching plate, a box thereon having an open face and an open side, a plate insertable through the open side into the box for display through the open face, said plate having ornamental means thereon susceptible to the action of heat, and means insertable between the attaching plate and the inserted plate for preventing conduction of heat to the inserted plate from the attaching plate.
5. A name plate for automobile radiators and the like including an attaching plate, a box thereon having an open face and an open side, a plate insertable through the open side into the box for display through the open face, said plate having ornamental means thereon susceptible to the action of heat, means insertable between the attaching plate and the inserted plate for pre-

venting conduction of heat to the inserted plate from the attaching plate, and means 25 for holding the inserted plate and insulating means within the box.

6. A name plate for automobile radiators and the like including an attaching plate, a box thereon having an open face and an 30 open side, a plate insertable through the open side into the box for display through the open face, said plate having ornamental means thereon susceptible to the action of heat, means insertable between the attaching plate and the inserted plate for preventing conduction of heat to the inserted plate from the attaching plate, and means for holding the inserted plate and insulating means within the box, said means including 35 a bendable portion integral with the box and movable to position across the open side thereof.

In testimony that I claim the foregoing as my own, I have hereto affixed my signature.

HENRY W. PETERS.
